(57) **CLAIM**

The ornamental design for a projectile as shown and described.

DESCRIPTION

FIG. 1 is a perspective view of a first embodiment of the projectile;

FIG. 2 is a perspective view of the projectile of FIG. 1;

FIG. 3 is a front view of the projectile of FIG. 1;

FIG. 4 is a back view of the projectile of FIG. 1;

FIG. 5 is a right side view of the projectile of FIG. 1, the left side being a mirror image of the right side;

FIG. 6 is a top view of the projectile of FIG. 1;

FIG. 7 is a bottom view of the projectile of FIG. 1;

FIG. 8 is a perspective view of a second embodiment of the projectile;

FIG. 9 is a perspective view of the projectile of FIG. 8;

FIG. 10 is a front view of the projectile of FIG. 8;

FIG. 11 is a back view of the projectile of FIG. 8;

FIG. 12 is a right side view of the projectile of FIG. 8, the left side being a mirror image of the right side;

FIG. 13 is a top view of the projectile of FIG. 8; and,

FIG. 14 is a bottom view of the projectile of FIG. 8.

The broken lines in the drawings depict portions of the projectile that form no part of the claimed design. The dash-dot broken lines depict portions of the projectile that form not part of the claimed design.

1 Claim, 14 Drawing Sheets
